UNITED STATES PATENT OFFICE.

ELI ODELL, OF WINTERSET, IOWA.

IMPROVEMENT IN PLANES.

Specification forming part of Letters Patent No. 41,317, dated January 19, 1864.

To all whom it may concern.

Be it known that I, ELI ODELL, of Winter-
set, Madison county, and State of Iowa, have
invented an Improvement on the Common
Plane in two particulars, as hereinafter de-
scribed, reference being had to the accompa-
nying drawings, and to the letters of reference
marked thereon.

The nature of my improvements are in the
two following particulars: First, the thread
of the plane is to be cut concave, instead of
convex, as in the usual form, thus entirely
preventing it from choking with shavings, as
is customary with the common form; second,
improvement is to prevent the enlargement of
the throat of plane as the face wears away by
use, which is done in the following manner:
Cut out to the depth of one inch (more or less)
the face of the plane from the throat to the
front end. Then cut a groove in the center
of the plane from the front end to the
throat on the under side. Then make a
separate piece to form that part of the face of
the plane cut out, and also to fit the groove
accurately. The object of this piece on the
face of the plane is to keep the throat of the
plane small as the face wears away by use,

and is done by cutting the shoulder at the
throat of the plane and sliding the face-piece
toward the bit, and is represented by the let-
ter B. Thus, the throat may be regulated in
size until the plane is worn out. Said face-
piece is moved by and held by two screws,
the one on the top, letter C, passing through
the upper part of the plane and down into let-
ter B into a nut that has play, that it can slide
along in a mortise in letter B. The other, in
the frontend, (represented by D,) connects with
a nut in a mortise in the upper part of the
plane, which nut hooks into letter B, which
can slide either to open or shut the throat. In
order to disconnect letter B (the face-piece)
from the plane, unscrew letter C until letter
B comes loose.

What I claim as new, and desire to secure
by Letters Patent, is—

A plane, with the adjustable face-plate B,
in combination with a concave throat, the
whole constructed and operated substantially
as described.

ELI ODELL.
